Primary Examiner — Robert M. Spear(74) *Attorney, Agent, or Firm* — Sughrue Mion, PLLC(57) **CLAIM**

The ornamental design for a tire tread, as shown and described.

DESCRIPTION

FIG. 1 is a perspective view of a tire tread showing our design;

FIG. 2 is a front view thereof;

FIG. 3 is a top view thereof;

FIG. 4 is a right side view thereof;

FIG. 5 is a left side view thereof;

FIG. 6 is a fragmentary enlarged front view;

FIG. 7 is an end view taken along line 7-7 in FIG. 6; and,
FIG. 8 is an end view taken along line 8-8 in FIG. 6.

Broken lines in the drawings are intended to show portions of the tire that are not being claimed, and thus form no part of the claimed invention.
